United States Patent Office

Des. 213,713
Patented Apr. 1, 1969

213,713

VEHICLE LIFT

Robert M. Tormey, 616 W. Siebenthaler Ave.,
Dayton, Ohio 45405

Filed Feb. 27, 1968, Ser. No. 10,751

Term of patent 14 years

Int. Cl. D12—05

U.S. Cl. D41—1

FIG. 1

FIG. 2

FIG. 3

FIG. 5

FIG. 4

FIGURE 1 is an isometric view of a vehicle lift embodying my new design;

FIGURE 2 is a top plan view thereof;

FIGURE 3 is a front elevational view thereof;

FIGURE 4 is a bottom plan view thereof; and

FIGURE 5 is a side elevational view thereof.

The dominant features reside in the solid line portions.

I claim:

The ornamental design for a vehicle lift, substantially as shown and described.
